[57] CLAIM

The ornamental design for a clothing hanger bracket for
automobiles, as shown and described.

DESCRIPTION

FIG. 1 is a perspective view of a clothing hanger
bracket for automobiles showing our new design;
FIG. 2 is a left side elevational view thereof, the side
opposite being a mirror image;

FIG. 3 is a front elevational view thereof;

FIG. 4 is a rear elevational view thereof;

FIG. 5 is a top plan view thereof; and

FIG. 6 is a bottom plan view thereof.

Fig. 1.
